UNITED STATES PATENT OFFICE

167,953

CABINET FOR A PHONOGRAPH REMOTE- CONTROL UNIT

David C. Rockola, Chicago, Ill., assignor to Rock-
Ola Manufacturing Corporation, Chicago, Ill., a
corporation of Delaware

Application February 16, 1951, Serial No. 14,240

Term of patent 14 years

(Cl. D26—14)

To all whom it may concern:

Be it known that I, David C. Rockola, a citizen of the United States and resident of Chicago, in the county of Cook and State of Illinois, have invented a new, original, and ornamental Design for a Cabinet for a Phonograph Remote-Control Unit, of which the following is a specification, reference being had to the accompanying drawing, forming a part thereof.

Figure 1 is a front elevation of a wall cabinet embodying my design;

Fig. 2 is a top plan view of the cabinet of Fig. 1; and

Fig. 3 is a side elevation as seen from the left side of Fig. 1.

The right hand side of the cabinet has the same configuration as that shown in Fig. 3, and the bottom and rear sides of the cabinet are plain.

The dominant features of my design reside in those portions shown in full lines.

I claim:

The ornamental design for a cabinet for a phonograph remote control unit, substantially as shown and described.

DAVID C. ROCKOLA.
